MOUNTING MEANS FOR SLIDING DOORS

David H. Morgan, Youngstown, Ohio

Application April 5, 1954, Serial No. 420,820

5 Claims. (Cl. 16—106)

My invention relates broadly to sliding doors for 15 hangars or piers and other large openings, and more particularly to a construction of floating top roller for such doors.

One of the objects of my invention is to provide a construction of floating top roller for doors including means for compensating for unevenness in the track over which the doors operate, and coacting means for guiding the doors in a vertical plane against abnormal wind pressures while providing means for insuring weather-tightness of the door even under conditions where a wide variation in the movement of the door over the base track may occur.

Another object of my invention is to provide a construction of floating top roller for sliding doors in which I-beams are provided for guiding the doors in vertical planes and wherein the top rollers each includes one set of diagonally disposed roller members which coact with the top surface of the lower flange of one of the I-beams on opposite sides of the intermediate web thereof, and another set of diagonally disposed roller members which coact with the opposite sides of the vertical web of the said I-beams for maintaining the door in an upright position and sustaining the door against abnormal wind pressures.

Another object of my invention is to provide a compact construction of floating top rollers which may be connected with the tops of the leaves of a multiple sliding door system and provide adequate clearance for the mutual sliding of the leaves and at the same time permit variation in the vertical position of the leaves for following unevenness in the base track level with provision for excluding rain, snow and ice adjacent the door suspension.

Other and further objects of my invention are to provide a strong and reliable structural assembly for guiding the multiple leaves of hangar and pier doors as set forth more fully in the specification hereinafter following by reference to the accompanying drawings, in which:

Fig. 1 is a front elevational view of a hangar or pier sliding door employing the floating top roller of my invention;

Fig. 2 is a top plan view showing the suspension for a pair of leaves of the hangar or pier door illustrated in Fig. 1;

Fig. 3 is a vertical sectional view taken substantially on line 3—3 of Fig. 2, showing the floating top rollers for guiding two coacting leaves of a hangar or pier door;

Fig. 4 is a fragmentary top plan view of one of the floating top roller units of my invention;

Fig. 5 is a horizontal sectional view taken substantially on line 5—5 of Fig. 3;

Fig. 6 is an enlarged fragmentary elevational view showing one of the floating top roller units of my invention;

Fig. 7 is a fragmentary elevational view partially in section showing the arrangement of the depending guide associated with the sliding door;

Fig. 8 is a vertical sectional view showing a modified

2

form of weathering shield which may be used with the floating top rollers of my invention; and

Fig. 9 is a schematic top plan view showing the location of the weathering shields with respect to each of the 5 coacting door leaves.

My invention is directed to a construction of floating top roller for sliding doors, hangars and piers by which the multiple leaves of a sliding door system, of heights of from eighteen to sixty-five feet or more, and of weights 10 of the order of 1200 lbs. to 30-tons, may be readily supported for overhead sliding and sustained in an upright position against abnormal wind pressures while providing means whereby the operation of the floating top roller remains effective even though the vertical dimension from the bottom of the overhead guide to the top of the base rail on the floor or ground may vary excessively, even up to the order of twelve inches without effecting the operation of the leaves while excluding the entry of snow, ice and rain between the roller track and the top of the 20 door leaf.

I accomplish these advantages by means of a compact floating top roller unit arranged to coact with an I-beam suspension. The floating top roller unit embraces the I-beam and contains one set of diagonally disposed roller 25 members which engage the top surface of the lower flange of the I-beam on opposite sides of the intermediate web thereof, while another set of roller members which are diagonally disposed engage opposite faces of the intermediate web of the I-beam. The coaction of the two 30 sets of roller members with the I-beam insures a uniform rolling movement of the coacting door leaves. The floating top roller units are mounted on opposite ends of the web of a downwardly directed channel member. I provide a weathering strip having one portion extending 35 upwardly adjacent the floating top roller units and supported by the channel and closing the gap between the floating top roller units and the lower flange of the I-beam, and another portion extending downwardly from the channel and overlapping with the top peripheral edge 40 of the pier or hangar door leaf. The two floating top roller units which are mounted adjacent opposite ends of the web of the channel member insure the steady horizontal movement of the channel member. The channel member carries downwardly extending guides. These 45 guides fit loosely through the top of the frame of the door leaf and serve to sustain the door leaf in an upright position while enabling the position of the door leaf to vary, both upwardly and downwardly, beneath the channel on which the floating top roller units are mounted and behind the downwardly depending weathering strip carried 50 by the channel whereby the door leaf, in operating over an uneven base track, will still be maintained in a sustained position with adequate weather protection between the floating top roller units and the peripheral edge of the 55 top of the door leaf.

The floating top roller unit forms with the interconnecting inverted channel a reliable guiding means for the sliding door leaf where the spaced depending guides enable the door leaf to rise and fall according to unevenness in the level of the base track while being sustained in a predetermined vertical plane, enabling the passage of similarly suspended coacting door leaves.

Referring to the drawings in more detail, reference character 1 designates a door leaf for a hangar, or pier, which is guided in an upright position by the floating top roller units 2 and 3. Each floating unit comprises a pair of welded frame sections shown at 4 and 5, and 6 and 7, respectively. The sections 4 and 5 are connected in off-set relation end-to-end. Similarly the sections 6 and 7 are connected end-to-end in off-set relation.

In Fig. 2 where the guide means for the coacting door leaf is shown, the floating top roller units are designated

at 2' and 3', respectively, comprising the adjacent welded frames 4' and 5' and 6' and 7'.

In Fig. 6 I have shown on an enlarged scale the arrangement of the two frames 4 and 5 which constitute the means for mounting the rollers in each of the floating top roller units. It will be observed that frame 4 provides at the side 4a thereof a journal for the roller 8 which is disposed on a horizontal axis and is directed inwardly to engage the upper surface of the lower flange of the I-beam 9. The frame 4 is integral with a base 10 plate 4b which extends horizontally and provides a support for a bracket 10. Bracket 10 is grooved at 11 to permit clearance of the edge of the lower flange of the I-beam 9, and also to provide journalling means for the roller 12. Roller 12 is mounted horizontally and makes contact with the vertical surface of the web of the I-beam 9, while roller 8 constitutes a vertical roller making contact with the top surface of the lower flange of the I-beam 9, as heretofore stated.

Rollers 8 and 12, journalled with respect to the frame 4, form part of the cluster of the floating top roller. The coacting frame 5 supports similar rollers but in diagonally opposite positions as illustrated more clearly in Figs. 2, 4 and 5. Frame 5, for example, includes an upwardly extending side portion indicated at 5a in which the vertical roller 14 is journalled for establishing rolling contact with the upper surface of the lower flange of the I-beam 9. The frame 5 extends horizontally, forming an integral base 5b adjacent the end of which there is mounted the bracket 15. Bracket 15 provides journalling means for the horizontal roller 16 which establishes contact with the opposite surface of the web of the I-beam 9 as compared to the position of roller 12. Thus it will be seen that the vertically disposed rollers 8 and 14 establish rolling contact with the top surfaces of the lower flange of I-beam 9 on opposite sides of the web thereof, while rollers 12 and 16 establish rolling contact with the opposite faces of the intermediate web of the I-beam 9 at diagonally opposed positions of the unit. In order to clarify the drawing I have shown the diagonally opposed horizontal rollers 12 and 16 somewhat spaced from the opposite surfaces of the web of the I-beam 9, but it will be understood that in practice the rollers establish close-fitting rolling contact with the opposite faces of the web of the I-beam. Customarily, graphite bronze bushings are used for journalling both the vertical rollers 8 and 14 and the horizontal rollers 12 and 16. It is possible, however, to use any anti-friction bearings, such as roller bearings, in one or both sets of rollers.

In order to withstand the severe strains to which the structure of my invention are subjected, I provide welded connections between the coacting frame sections 4 and 5 and secure the brackets 10 and 15 to the bases 4b and 5b by means of screws 17 and 18. The edge of the side 4a is welded to the abutting face of the bracket 15 at substantially the center thereof in frame 4. Similarly the edge of the side 5a is welded to substantially the center of the bracket 10 in frame 5. The frame sections 4 and 5 and 6 and 7 are all symmetrical, that is, there are no "rights" or "lefts" and the roller units 2 and 3 constitute assemblies of two each of these frame sections reversed in position with respect to each other where one frame section extends beyond the horizontal limit of the coacting frame section of each unit in the opposite direction. Fig. 2 shows, for example, section 4 extending beyond the side of section 5 at one side while at the other side section 5 extends beyond the side of section 4. This symmetry is uniform for sections 4' and 5' and also for sections 6 and 7 and sections 6' and 7'. Thus the pattern of each section is the same but by reversing the positions of the sections and welding the sections end to end a composite suspension assembly is obtained without right and left patterns. The screws 17-20 extend through the flanges 21, 22, 23 and 24 connected with the guide rods 25, 26, 27 and 28 as shown more

clearly in Fig. 7. The screws pass through the bases 4b and 5b and through the web of the weathering channel 29, passing through the flanges 21-24 and being secured by nuts 17a, 18a, 19a and 20a. The depending guide rods 25-28 pass slidably through the top frame portions of the door leaf 1, as shown more clearly in Fig. 3. The door leaf 1 may include the horizontally extending frame members 30 and 31 adjacent the top thereof consisting of channels with their flanges directed upwardly and closed by web plates 32, 33, 34, 35, and 36, 37, 38 and 39. The channels and the associated web plates are apertured for the slidable passage of the depending guide rods 25-28 whereby the door leaf 1 is free to vary in position vertically with respect to the guide rods. Confining nuts and washers 25a, 26a, 27a and 28a are secured to the free depending ends of the guide rods 25-28, respectively. These confining nuts and washers 25a-28a are not essential and may be omitted as the guide rods will perform their guiding function without such confining washers and nuts, although such washers and nuts do serve as a supporting means for the door leaf in instances where the uneven track bed 40, over which the bottom wheels 41 and 42 operate, may fall below a safe limit or through some obstruction on the track the door leaf might leave the rail and slip from the ends of the guide rods 25-28. Such a condition has been encountered where the door encounters a reasonably small obstruction, jumping the bottom wheels 41 and 42 off the rack 40, whereupon the door leaves 40 confined by the washers and nuts 25a-28a may slip from the guide rods. The bottom wheels 41 and 42 operating over rail 40 have been illustrated schematically and represent any trackage arrangement for minimizing the dislodgement of the door leaf by reason of obstructions of any kind. In practice the bottom wheels 41 and 42 may have a diameter ranging from 9 inches to 24 inches for supporting a mass in the range of 1200 lbs. to 30 tons. Thus it will be seen that the door leaf is free to rise and fall on the guide rods within certain limits 40 which are the reasonable limits to which an installation of this kind may be expected to be subjected.

The weathering channel 29 supports the weathering angles 43 and 44, as indicated in Figs. 4 and 5, extending between the floating top roller units. While I have illustrated two of such weathering angles 43 and 44 in Figs. 4 and 5, a single angle may be sufficient as illustrated in Fig. 3. These angles are adjustable on the web of the weathering channel 29 after the door is installed in order to reduce the gap between the angle and the edge of the lower flange of the I-beam 9 to a minimum. The weathering channel 29 also carries a weathering shield 45, depending downwardly and shaped to coact with the top peripheral edge of the door leaf 1. Thus, as the door leaf 1 rises and falls on the guide rods 25-28, beneath the weathering channel 29, entry of rain, snow or ice is prevented by the overlapping of the weathering shield 45 with the top periphery of the door. This weathering shield 45 extends around the leading edges of the door leaf where it precludes entry of the elements. As shown in Figs. 8 and 9 the weathering shield 45 may be supported from the overhead structure adjacent the tops of the overhead structure, represented at 46. In this instance the weathering shield is a stationary sheet as represented at 47. These sheets extend for the width of the door leaves when in their closed position when the door leaves are moved to overlapping relation for closing the hangar or pier doors opening as represented in Fig. 9. These shields 47 form a closure adjacent the tops of the door leaves preventing entry of the elements.

The overhead structure indicated at 46 may take a variety of forms. In the case of wood trusses, drying out of the wood and the loosening of the associated ring connectors often has the effect of changing the spatial relation of the parts of the supporting structure in reference to the base rails 34 on the floor. The structure of my

invention compensates for conditions of this kind. Also, in the case of snow-loads on the roof of a building the spatial relation of parts of the supporting structure with reference to the base rails 34 may change and such changes are compensated for by the structure of my invention. Changes in temperature conditions on metal supported structures also have adverse influences upon conventional types of sliding door mountings. This is particularly true in a three-pinned arch system and cantilever structures for all of which the arrangement of my invention compensates for those inequalities in height.

In the several views illustrating the multiple door leaves I have applied primed reference characters to those parts which indicate corresponding elements of the principal door leaf. That is, the reference characters have been repeated on the coacting door leaf, but simply primed to show the corresponding parts.

While I have described my invention in certain of its preferred embodiments I realize that modifications may be made, and I desire that it be understood that no limitations upon my invention are intended other than may be imposed by the scope of the appended claims.

What I claim as new and desire to secure by Letters Patent of the United States is as follows:

1. A hanger for sliding doors for guiding the movement of a door with respect to an I-beam having a vertical web and an upper and lower horizontal flange, comprising a two section frame whose sections are substantially identical and are assembled in positions reversed with respect to each other and connected end-to-end in abutting relation and adapted to be attached to the top of a slideable door and embracing the lower horizontal flange of the I-beam and extending upwardly on opposite sides of the web thereof, two roller members journaled in each frame section, one roller member of each frame section being journaled for rotation in a vertical plane and engaging the top surface of the lower horizontal flange of the I-beam on one side of the web thereof and the other roller member of each frame section being journaled for rotation in a horizontal plane and engaging the opposite side of the said web for guiding the movement of the door.

2. A hanger for sliding doors as set forth in claim 1 in which each of said frame sections includes a vertically extending side member with the side member of one section disposed in a position that is spaced from the side of the web and laterally spaced with respect to the position of the side member in the adjacent frame section, and wherein, the roller members engageable with the top surface of the lower horizontal flange of the I-beam are journaled in the vertically extending side members, and a bracket forming part of each frame section, the roller members engageable with the opposite sides of the web of the I-beam being journaled in said brackets.

3. A hanger for sliding doors as set forth in claim 1 in which each of said frame sections includes a vertically extending side member with the side member of one frame section disposed in a position on one side of the web and laterally spaced with respect to the vertically extending side member of the adjacent frame section, and wherein said roller members engageable with the top surface of the lower flange of the I-beam are journaled in the said vertically extending side members, and

brackets located in each of said frame sections in opposite positions therein, the roller members engageable with the opposite sides of the web of the I-beam being journaled in said brackets, and wherein said side members are off-set from the longitudinal extremities of the lower horizontal flange of the I-beam, and said brackets each being provided with a longitudinally extending groove which embraces in spatial relation the longitudinal extremities of the lower horizontal flange of the I-beam.

4. A hanger for sliding doors as set forth in claim 1 in which each of said frame sections includes a bracket for journaling the roller members which engage the opposite sides of the web of the I-beam and wherein said brackets form substantially a loop substantially encircling said last mentioned roller members with the loops extending laterally substantially diametrically of the last mentioned roller members and with the said roller members projecting beyond the sides of said brackets for engaging the opposite sides of the web.

5. A hanger for guiding the movement of a sliding door with respect to an I-beam having a vertically extending web and an upper and lower horizontal flange comprising an inverted channel having a horizontally extending rear web and a pair of downwardly depending vertically disposed side flanges extending in a direction parallel with the direction of movement of a sliding door arranged beneath said channel, a pair of frame sections supported in linearly spaced positions with respect to said rear web of said inverted channel, said frame sections extending upwardly to positions above the lower horizontal flange of said I-beam and terminating substantially centrally of the vertically extending web of the I-beam, each of said frame sections being substantially identical and disposed in abutment end-to-end in reversed positions, said sections each including a transversely extending wall structure at one side of the web of said I-beam and a longitudinally extending wall structure spaced from the opposite side of said web and wherein the longitudinally extending wall structure of one frame section is connected with the transversely extending wall structure of the adjacent frame section substantially at the center thereof and laterally spaced from the sides of the web of the I-beam, a pair of roller members journaled in each of said frame sections, one roller member of each frame section being journaled on said longitudinally extending wall structure and engaging the upper surface of the lower horizontal flange of said I-beam at one side of the web and the other roller member of each frame section being journaled intermediate said transversely extending wall structure and engaging the side of the web in a position directly opposite the position of the aforesaid roller member.
